UNITED STATES PATENT OFFICE.

ROBERT J. OWENS, OF MINNEAPOLIS, MINNESOTA.

62

MILK-CAN CLEANER.

1,009,470.

Specification of Letters Patent. Patented Nov. 21, 1911.

Application filed August 12, 1910. Serial No. 576,817.

To all whom it may concern:

Be it known that I, ROBERT J. OWENS, a citizen of the United States, residing at Minneapolis, in the county of Hennepin and State of Minnesota, have invented certain new and useful Improvements in Milk-Can Cleaners; and I do hereby declare the following to be a full, clear, and exact description of the invention, such as will enable others skilled in the art to which it appertains to make and use the same.

My invention has for its object to provide an improved device for cleaning milk cans and similar vessels and to this end the invention consists of the novel devices and combinations for devices hereinafter described and defined in the claims.

In the accompanying drawings, which illustrate the invention, like characters indicate like parts throughout the several views.

Referring to the drawings: Figure 1 is a view in vertical section showing the improved cleaner, some parts being shown in full and some parts being broken away. Fig. 2 is a transverse section on an enlarged scale taken on the line $x^1 x^2$ of Fig. 1. Fig. 3 is a section on an enlarged scale taken on the line $x^3 x^4$ of Fig. 1 showing the radially extensible brush carrier contracted so that it may be freely passed through the neck of the can; and, Fig. 4 is an end elevation of the brush and its extensible carrier as shown in Fig. 2.

The milk can 1 which is shown as a stand-and construction is adapted to be detachably held in an inclined position upon any suitable supporting frame 2, having an upwardly extended inclined arm 3 terminating in a gear nest 4 having axially aligned bearing sleeves 5. Bushings 6 are journaled in the sleeves 5 of the gear nest 4, but are held against endwise movements by any suitable means not illustrated. A beveled pinion 7 is formed as a part of or otherwise rigidly secured to the lower bushing 6 and this pinion meshes with a beveled gear 8 suitably journaled in the gear nest 4 and provided with an operating hand crank 9. A long square shaft 10 is mounted to slide endwise through the bushings 6 and to rotate therewith and with the pinion 7. A hand piece 11 is swiveled at 12 to the outer or upper end of the shaft 10.

The outer or lower end of the shaft 10 fits in a square seat 13 of a central brush carrying head 14 and is adapted to be rigidly

but detachably secured thereto by set screw 15. This head 14 is provided with diametrically opposite pairs of arms 16 to which extensible brush carrying arms 17 are pivotally connected at 18. One or more of these arms 17 is provided with a projecting stop lug 19 that is engageable with a stop shoulder 20 on the arm 16 to which it is pivotally connected, to thereby limit the extreme outward movements of the said arms 17.

The free ends of the extensible arms 17 are rigidly connected in pairs to the rigid backs of brushes 21. The upper end portions of the said brushes 21 are preferably extended inward, as shown in Fig. 1, to adapt the brushes to closely engage the upper body portion of the can adjacent to the neck thereof. The arms 17 that are adjacent to the bottom of the can, are rigidly secured to the backs of brushes 22, and the corresponding arms 16 of the head 14 are secured to a brush 23. The brushes 22 and 23 are adapted to clean the bottom of the can while the brushes 21 are adapted to clean the sides of the can.

For imparting simultaneous inward and simultaneous outward movements, to the extensible brushes 21 and 22, a small lever 24 is intermediately pivoted on a hub formed at one end of the head 14, and the opposite ends of this lever 24 are connected by links 25, to the upper extensible arms 17, at points eccentric to their pivotal connections 18.

When the brush is to be inserted into the can or to be removed therefrom through the neck thereof, the parts which make up the brush carrier or support are folded together, as shown in Fig. 3. When the brush is located within the can it may be rotated by manipulation of the hand crank 9, and when rotated the extensible brushes 22 and 23 will be thrown outward by the turning of the hand crank 9 and will be held in contact with the inner surface of the can. Centrifugal force will also tend to hold the brushes 22 and 23 in contact with the inner surface of the can. As both brushes move simultaneously equal distances from the axis of the shaft 10, it follows that the said shaft 10 will always be held with the axis coincident with the longitudinal axis of the can. When the brush is forced downward to the position shown in Fig. 1 it will clean the bottom of the can and the lower side portions thereof. To clean the inner surface of the upper portion of the can, the brush is moved

axially within the can, and this may be readily accomplished by pulling upward on the swiveled hand piece 11. This hand piece gives complete control of the endwise or axial movements of the brush without any way interfering with the rotation of the brush.

The device while simple and of small cost has in practice been found highly efficient for the purpose had in view.

What I claim is:

1. In a can cleaner, the combination with a shaft with a brush carrying head at one end thereof, of extensible brushes with the arms pivotally connected to said head, a lever intermediately pivoted to said head and links directly connecting the ends of said lever to the arms of said brushes, for imparting simultaneous outward and simultaneous inward movements of the said brushes.

2. In a can cleaner, the combination with a shaft provided at one end with a head having radially extended pairs of arms, of brushes having arms connected to the arms of said head by pivots, the axes of which are parallel to the axis of said shaft, a lever intermediately pivoted to said head, and links directly connecting the ends of said lever to the intermediate portions of diametrically opposite arms of the said extensible brushes.

3. In a can cleaner, the combination with a shaft provided at one end with a head having diametrically extended pairs of arms, of extensible brushes having pairs of arms connected to the arms of said head by pivots, the axes of which are parallel to the axis of said shaft, brushes applied to the arms of said extensible brushes and to the arms of said head, at one end of the device, a lever intermediately pivoted on one end of

the said head, and links directly connecting the ends of said lever to the intermediate portions of adjacent arms of the said extensible brushes, substantially as described.

4. In a can cleaner, the combination with a frame work arranged to support a can in an inclined position, of a gear nest on an upwardly extended portion of said frame and an intermeshing beveled pinion and gear mounted on said gear nest, a crank connected to said gear, a shaft mounted to rotate with but to slide in said pinion, a hand piece swiveled to the upper end of said shaft, a head secured to the lower end of said shaft and provided with diametrically extended pairs of arms, extensible brushes having arms pivotally connected to the arms of said head, and brushes applied to the lower end arms of said head, substantially as described.

5. In a can cleaner, the combination with a shaft provided at one end with a head having diametrically extended pairs of arms, of extensible brushes having pairs of arms connected to the arms of said head by pivots, the axes of which are parallel to the axis of said shaft, brushes applied to the arms of said extensible brushes and to the arms of said head, at one end of the device, a lever intermediately pivoted on one end of the said head, links directly connecting the ends of said lever to the intermediate portions of adjacent arms of said extensible brushes, and stops for limiting the outward movement of the arms of said extensible brushes, substantially as described.

In testimony whereof I affix my signature in presence of two witnesses.

ROBERT J. OWENS
